ATTORNEYS

UNITED STATES PATENT OFFICE.

JOHN MARSH, OF CHICAGO, ILLINOIS.

CONTAINER.

1,239,417.

Specification of Letters Patent. Patented Sept. 4, 1917.

Application filed October 24, 1916. Serial No. 127,362.

To all whom it may concern:

Be it known that I, JOHN MARSH, a citizen of the United States, and a resident of Chicago, in the county of Cook and State 5 of Illinois, have invented certain new and useful Improvements in Containers, of which the following is a specification.

My invention relates to containers, with a particular adaptation to paint, and the 10 main object thereof is to provide, in combination with a conventional can, a receptacle for a portion of the contents of the can, after the latter has been opened, forming a component part of the can and portable therewith.

Paints vended in cans have a tendency to settle in the bottoms of the cans from long standing in one position, leaving the liquid thinners at the top, and paint manufacturers 20 in their printed instructions advise that a portion of the thinner be poured from the can to allow stirring of the relatively thick remainder and, after an even consistency of the latter has been attained, the removed 25 thinner may be gradually added during the continued stirring of the paint until the original consistency is obtained by having all the removed thinner mixed thoroughly with the can's contents.

Almost invariably, upon opening a can of paint, the person opening it has no receptacle for the thinner at his command and he must either lose time in searching for one or he must spill the thinner in his effort to stir 35 the contents of the can without first removing some of the thinner, and it was in order to overcome this loss of either time or material that my invention was conceived.

My invention is fully described in the following specification, of which the accompanying drawings form a part, in which like characters refer to like parts in each of the views, and in which:—

Figure 1 is an elevation of a conventional 45 paint can having a frictionally held cover and provided with my invention, part of the can being shown in central vertical section;

Fig. 2 is a view of the cover removed and inverted, showing my invention in section, ready for use; and

Fig. 3 is a view similar to Fig. 1 but showing the cover as of the rolled seam type, usually of thin metal adapted to be cut as 55 by means of a knife or a can opener.

Referring to the drawings, 4 represents a

paint can of any desired form or size having a cover 5 secured thereto in any manner which prevents leakage in transportation and guards against the admission of air to the can to prevent evaporation of the contents.

Secured to the inner surface of the cover 5 is a normally dependent member 6 forming, with the cover 5 to which it is secured, 65 a cup normally inverted, shown as cylindrical and of a smaller diameter than the can 4, and being shown as of materially less depth than the can.

When the cover 5 is detached from the can the member 6 is removed therewith and, after permitting the paint adhering thereto to drip into the can, the cover is reversed to carry the member 6 above the cover and thus adapt the member 6 and the portion of the 75 cover inclosed thereby for use as a receptacle for a portion of the contents of the can and, in the stirring of the remainder of the contents in the can, the thinner in the said receptacle may be gradually added to 80 the thicker portion in the can until all of said thinner has been mixed with the thicker portion of the contents of the can and said contents are now ready for use as contemplated by the paint manufacturer. 85

If the now thoroughly mixed paint is to be used from the can, a portion of said paint may be poured into the receptacle 6, or said receptacle may be used by the painter to carry a relatively small amount of paint, 90 replenishing said receptacle from time to time from the larger can, the portion of the cover outside of the member 6 serving as a receiver for any paint which might be on the outside of the member 6 or which might 95 be spilled from said member during the use of the paint therein.

The receptacle 6 serves a further purpose by permitting tinting a portion of the paint originally in the can 4, as for instance where 100 two shades of color are desired at one time; in other words, the functions of the can are doubled by means of my invention.

Further, in the rough handling which paint cans are subject to, it frequently happens that the relatively thin cover shown in Fig. 3 may be dented sufficiently to strain the seam at its junction with the can 4 and start a leak, but when my member 6 is used the cover is materially strengthened and this 110 liability to injury to the cover is correspondingly lessened.

My invention is thoroughly practical, of great advantage to paint users, occupies but little space in the can, and adds little to the weight or to the cost of the can, and I reserve the right to make the member 6 of any size or shape and to attach the same to the cover in any desired manner, and to use the same with any type of can for either paint or other material.

10 Having fully described my invention, what I claim as new, and desire to secure by Letters Patent, is:—

As a new article of manufacture, a paint can provided with a flat cover free from 15 projections on its outer face and provided

on its inner face adjacent the periphery with an annular inwardly bent portion serving to secure it on the can, and a short distance from the inwardly bent portion with a tubular member open at its inner end and spaced 20 from the sides of the can, said tubular member being of considerable length and forming with the cover when removed a receptacle for holding a portion of the contents of the can and a drip receiver therefor.

JOHN MARSH.
